UNITED STATES PATENT OFFICE.

JOSEPH DECLAYE, OF LIEGE, BELGIUM.

GUNLOCK DEVICE OF SMALLARMS.

Application filed September 10, 1920. Serial No. 409,381.

To all whom it may concern:

Be it known that I, JOSEPH DECLAYE, a subject of the King of Belgium, and resident of Liege, Belgium, 32 Rue Adolphe Borgnet, have invented certain new and useful improvements in or Relating to Gunlock Device of Smallarms; and I do hereby declare the following to be a full, clear, and exact description of the invention, such as 10 will enable others skilled in the art to which it appertains to make and use the same, reference being had to the accompanying drawings, and to letters or figures of reference marked therein, which form a part of this 15 specification.

This invention relates to small-arms of the repeating or automatic type, and it relates particularly to a gun-lock device comprising a trigger on which is pivoted a lever 20 acting on the sear which cocks the striker.

In the gun-lock device according to this invention the lever pivoted on the trigger acts on one end of a projection on the sear and enters in a recess lowering in front of 25 the said elevation soon after firing, thus allowing the sear to cock the striker again when the breech bolt is recoiling.

The movements of the lever pivoted on the trigger may be controlled by the 30 motions of the breech bolt. For this purpose a second lever pivoted on a magazine lug may be utilized, this second lever acting on the first lever above mentioned, and being provided with a finger the end of which engages in a groove formed in the breech bolt. 35

When it is used with a tubular magazine disposed in the stock, the trigger may be arranged under this magazine and the sear above it, the lever pivoted on the trigger 40 being on one side of the magazine and the lever pivoted on the magazine lug passing on the other side of it.

The accompanying drawings illustrate the 45 application of the invention to an automatic rifle.

In the drawings:

Fig. 1 is a longitudinal section of the rifle, this section showing the gun-lock device;

Fig. 2 is a perspective view of the gun- 50 lock device;

Fig. 3 is an underneath perspective view of the gun-lock device;

Fig. 4 is a perspective view showing the 55 pieces of the gun-lock device in another position;

Fig. 5 shows in perspective the assembly of the gun-lock pieces with the tubular magazine; and

Fig. 6 shows in perspective the front end 60 of the sear.

On the trigger 2 pivoted at 10, a lever 1 is pivoted at 11. For firing this lever acts downwardly on a projection or elevation 12 provided on the sear 3, which sear is pivoted at 13. The downward action of the 65 lever 1 on the sear 3 pushes the nose 14 of the sear down, thus releasing the striker 15, which then moves to strike the firing-pin 25. When the breech bolt 5 is recoiling, the groove 8 with which it is provided leaves 70 the end of the finger 7 which was engaged in it. The said finger is a part of a lever 6 pivoted at 17 which acts by an arm 18 on the lever 1 pivoted on the trigger, when the finger 7 is forced down by the recoiling of 75 the bolt 5. The backward movement of the groove 8 pushes the end of the finger 7 out of it, thrusting said finger down and forcing the lever 6 to turn about its axis 17, its arm 18 thus acting against the lever 1 to make 80 it turn in the direction indicated by the arrow X. This lever 1 upon leaving the projection 12 on which it was resting, is brought above the recess 4 so that the sear 3 acted upon by the sear spring 19 assumes a position allowing it to cock the striker 15 during the recoiling movement of the latter. 85

In order to prevent the lever 1 from coming against the bottom of the recess 4, the pulling of the trigger may be limited by an 90 appropriate abutment, this abutment being intended to act in such a way as to prevent a lowered position of the lever 1 which would prevent the raising of the nose 14 of the sear to cock the striker. 95

When the breech bolt 5 has assumed its forward position and the trigger has been released, the said trigger acted upon by the trigger spring 9 resumes its initial position and the lever 1 acted by its spring 16 turns 100 round its axis 11 thus bringing its finger back over the elevation 12 of the sear. By this rotation of the lever 1, the lever 6 moves so that its finger 7 again enters the groove 8 of the bolt 5. 105

Fig. 5 shows how the pieces of the described gun-lock device may be disposed around a tubular magazine 21; the trigger 2 under this magazine, the sear 3 above it, the lever 1 pivoted on the trigger passing in 110

one side of it and the lever 6 passing on the other side.

The safety device acts upon the sear 3 and is made up of a detent 20 arranged in 5 the usual manner.

While the invention has been illustrated in what is considered its best application it may have other embodiments without departing from its spirit and is not therefore limited 10 to the structures shown in the drawings.

What I claim is:

1. A gun lock device for automatic repeating small arms, comprising, in combination, a trigger, a movable lever pivoted on 15 the trigger, a pivoted sear having a shoulder disposed so as to be acted upon by the movable lever, there being mechanism for moving said lever at the beginning of recoil away from said shoulder, and over a rigid 20 part of the sear disposed between its pivoted center and its operated extremity.

2. A gun-lock device for repeating small-arms comprising in combination a trigger, a sear having intermediate its ends an eleva- 25 tion adapted to be acted upon by a lever pivoted on said trigger and acting on said elevation to accomplish the firing, said sear

having a lowered surface in front of said elevation, said lever moving over said lowered surface after the firing operation whereby 30 the sear is permitted to again engage the striker when the breech-bolt is returning to firing position, and a second lever actuating the first mentioned lever and provided with a finger adapted to move in and out of a 35 groove on the breech-bolt as the said bolt reciprocates.

3. In a repeating small-arm the combination with a magazine, of a trigger beneath the magazine and pivoted thereto, a sear 40 above said magazine and pivoted thereto, a lever pivoted on the trigger and acting on said sear, and a second lever actuating the first mentioned lever and actuated by the breech-bolt.

4. A device as in claim 1, the upper end of said lever moving substantially parallel to the longitudinal axis of the sear.

In testimony whereof I affix my signature in presence of two witnesses.

JOSEPH DECLAYE.

Witnesses:

ALFRED VANDER HAEGHANY,
CH. MERCHIL.
